UNITED STATES PATENT OFFICE.

NIM WILLIAMS, OF ASHLAND, KENTUCKY.

DESIGN FOR A COMBINED HAT AND COAT RACK AND UMBRELLA-STAND.

57,066.

Specification for Design.

Patented Feb. 1, 1921.

Application filed August 31, 1920. Serial No. 407,276. Term of patent 14 years.

To all whom it may concern:

Be it known that I, NIM WILLIAMS, a citizen of the United States, residing at Ashland, in the county of Boyd and State of Kentucky, have invented a new, original, and ornamental Design for a Combined Hat and Coat Rack and Umbrella-Stand, of which the following is a specification, reference being had to the accompanying drawing, forming part thereof.

The figure is a perspective view of a combined hat and coat rack and umbrella stand, showing my new design.

I claim:

The ornamental design for a combined hat and coat rack and umbrella stand, as shown.

NIM WILLIAMS.
